US0D1071176S

(12) **United States Design Patent** (10) Patent No.: **US D1,071,176 S**
(45) Date of Patent: ** Apr. 15, 2025

(54) **OSTOMY APPLIANCE ELECTRONIC PATCH**

(71) Applicant: **Coloplast A/S**, Humlebaek (DK)

(72) Inventors: **Stephanie Knoedler**, Niva (DK);
Kamilla Grove Sund, Alleroed (DK)

(73) Assignee: **Coloplast A/S**, Humlebaek (DK)

(**) Term: **15 Years**

(21) Appl. No.: **29/888,835**

(22) Filed: **Apr. 5, 2023**

Related U.S. Application Data

(62) Division of application No. 29/752,442, filed on Sep. 28, 2020, now Pat. No. Des. 986,164.

(57) **CLAIM**

The ornamental design for an ostomy appliance electronic patch, as shown and described.

DESCRIPTION

FIG. 1 is a perspective view of an ostomy appliance electronic patch showing a new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top side elevation view thereof; and,

FIG. 7 is a bottom side elevation view thereof.

In FIGS. 1-7, the broken lines form no part of the claimed design.

1 Claim, 7 Drawing Sheets
